WIRING REEL & TOOLS CO., INC., OF NEW YORK, N. Y., A CORPORATION OF NEW
YORK.

SUPPORTING-REEL FOR WOUND COILS.

1,147,680.

Specification of Letters Patent. Patented July 20, 1915.

Application filed July 24, 1914. Serial No. 852,839.

To all whom it may concern:

Be it known that I, FRANK CRAWFORD, a citizen of the United States, and a resident of the city of New York, borough of Manhattan, in the county and State of New York, have invented a new and Improved Supporting-Reel for Wound Coils, of which the following is a full, clear, and exact description.

10 Among the principal objects which the present invention has in view are: to avoid any retardation or drag on a coil when unwinding the same; to provide an expansible core for a coil while being unwound; to provide simple and operatively manipulated means for securing a coil in a reel of the character described; and to provide a simple structure, the operation whereof serves automatically to exert a braking influence on the 15 rotating structure when paying out the strand of which the coil is constructed.

20 *Drawings.*—Figure 1 is a plan view of a reel constructed and arranged in accordance with the present invention, showing in conjunction therewith a coil of wound wire; Fig. 2 is a vertical section taken on the line 2—2 in Fig. 1.

25 *Description.*—As seen in the drawings, the reel proper has a basket-like structure, embodying a ring rim 7. The rim 7 is rigidly united to and supported upon the ends of vertical extensions 8 of radial arms 9. The inner ends of the arms 9 are rigidly connected to a central plate 10. The plate 10 is 30 recessed to form sockets for the ends of the arms 9, which are clamped therein by a base plate 11, from which extend upward the standard arms 12.

35 The plates 10 and 11 are structurally 40 united by screws 13, shown best in Fig. 1 of the drawings, and the arms 12 are integrally formed with a head 14, wherein is formed a socket 15, and extended from the top whereof are pivot supporting flanges 16. The 45 socket 15 is utilized to form a housing for the end of a pivot post 17 and a pivot ball 18, which is mounted upon said pivot post, or between the same and the inner end of the 50 socket 15. The ball 18, when disposed as above described, constitutes a rolling pivot for the basket-like structure of the reel, permitting the same to move easily about the post 17 and the face plate 19 upon which 55 said post is mounted. The spread of the

plate 19 varies in correspondence with the 55 service wherein the reel is employed. From the edge of the plate is extended a curved stripping arm 20, the upper end of which is provided with an inward extension 21, whereon is loosely mounted a guide ring 22. 60 Through the guide ring 22 the loose end 23 of the coil 24 is carried, to be guided thereby when unwound from the coil. The coils such as indicated by the numeral 24 are usually 65 flat, and are provided with a hollow or vacant center. Within this center are disposed framing bars 25. The bars 25 are preferably constructed from strap metal, having at the lower end a twisted guide section 26, through a perforation in which, one of the 70 arms 9 is passed. The perforation in the section 26 is sufficiently close to clamp on its respective arm when said bar is moved out of perpendicular relation to the arm 9. The framing bars 25 are supported in the up- 75 right position by handle bars 27, each of which is united to one of the framing bars by a link 28. The links 28 are pivoted one to each of the bars by bolts 29. Each of the links is clamped to one of the handle bars 27 80 by means of a wing nut 30. The handle bars 27 are each pivotally mounted upon one of the flanges 16 by a bolt 31. Each of the handle bars 27 is extended to overhang the rims 7 to prevent the coil 24 jumping from 85 the basket-structure formed by said rim and the arms 9, as above described.

90 *Operation.*—When employing a reel constructed and arranged as above described and as shown in the accompanying drawings, the coil 24 is placed in the basket structure to rest on the arms 9 within the rims 7. Prior to placing the coil, the wing nuts 30 95 are loosened to permit the free play of the links 28 and bars 25 and 27. The handle bars 27 are then engaged by the attendant, and raised to a vertical position above the pivot post 17. This operation draws the framing bars 25 toward the plate 10, the lower end of said bars sliding freely on the 100 arms 9 with which they are connected. The coil 24 is then lifted into the basket of the reel, the arms 27 and parts connected therewith extending upward through the central opening in the coil. The coil is now adjusted by the attendant lowering the bars 105 27 until the framing bars 25 move into contact with the inner edge of the coil 24. In

the adjustment of the coil to the reel, the bars 27 facilitate the placement thereof in concentric relation to the reel. The disproportionate height of the end of any one of 5 the bars 27 signifies a proportionate displacement of the coil within the rim. The bars 25 having been adjusted to the coil, the wing nuts 30 are tightened to hold the bars 25 and 27 in their adjusted positions. The 10 free end 23 of coil 24 is now threaded through the guide ring 22, and the operation of unreeling the wire from the coil is proceeded with. If, in the operation, the handling of the wire after passing outward 15 through the ring 22, is retarded, it immediately operates as a brake by the outermost one or more coils of wire spreading to contact with the extensions 8 of the basket frame, thereafter operating as a brake or 20 check on the running of said frame.

While I have herein described the invention in its application to coils of wire, it will be understood as being equally applicable in service, for unreeling coils of rope, twine, 25 or other material.

Claims:

1. A reel having a basket portion embodying a plurality of radial arms, each providing perpendicular retaining extensions; 30 a suspension structure for said basket portion, embodying an upraised bearing socket; a base plate; a pivot post rigidly mounted on said plate and extending above the bottom of said basket portion; a guide arm 35 mounted on said base plate, infolding the side of said basket portion and extending inward thereover; and means provided on said arm for guiding material leaving said basket portion.
- 40 2. A reel having a basket portion embodying a plurality of radial arms, each having a perpendicular retaining extension; a suspension structure for said basket portion, embodying an upraised bearing socket and a guide plate disposed at the lower end of 45 said structure; a base plate, a pivot post rigidly mounted on said base plate and extending upward through said guide plate into said bearing socket; a guide arm mounted on said base plate, infolding the side of said basket portion and extending inward thereover; and means provided on said arm for guiding material leaving said basket portion.
- 50 5. A reel having a basket portion embodying a plurality of radial arms; an expanding core, embodying a plurality of vertical arms, said arms being slidably mounted on said radial arms; and a plurality of centrally-disposed and pivotally-mounted toggle members for moving said vertical arms out from the center of said basket portion, said toggle members each embodying a handle-bar extending outward from the center of said basket portion for disposition 55 in superposed relation to said basket portion beyond said vertical arms.

ing a plurality of radial arms, each having a perpendicular retaining extension; a suspension structure for said basket portion, embodying an upraised bearing socket and a guide plate disposed at the lower end of 60 said structure; a base plate, a pivot post rigidly mounted on said base plate and extending upward through said guide plate into said bearing socket; a rolling bearing member mounted upon said pivot post within 65 said socket bearing; a guide arm mounted on said base plate, infolding the side of said basket portion and extending inward thereover; and means provided on said arm for guiding material leaving said basket portion. 70

4. A reel having a basket portion embodying a plurality of radial arms, each having perpendicular side-forming extensions, and a ring structurally uniting said extensions; 75 a suspension structure for said basket portion, embodying an upraised bearing socket and a guide plate disposed at the lower end of said structure; a base plate; a pivot post rigidly mounted on said base plate and extending upward through said guide plate into said bearing socket; a rolling bearing mounted upon said pivot post within 80 said socket bearing; a guide arm mounted on said base plate, infolding the side of said basket portion and extending inward thereover; and means provided on said arm for guiding material leaving said basket portion. 85

5. A reel having a basket portion embodying a plurality of radial arms; an expanding core, embodying a plurality of vertical arms, said arms being slidably mounted on said radial arms; and a plurality of centrally-disposed and pivotally-mounted toggle members for moving said vertical arms out from the center of said basket portion, said toggle members each embodying a handle-bar extending outward from the center of said basket portion for disposition 95 in superposed relation to said basket portion beyond said vertical arms. 100

In testimony whereof I have signed my name to this specification in the presence of two subscribing witnesses.

FRANK CRAWFORD.
